UNITED STATES PATENT OFFICE

DAVID COHEN, OF BROOKLYN, NEW YORK

VENTILATED SHOE

Application filed May 26, 1931. Serial No. 540,143.

This invention relates to an improvement in footwear, such as shoes, boots and the like, and is more particularly designed for the provision of effective constant and proper ventilation of the foot.

The serious and objectionable tendency of the foot to perspire is well known and many efforts have been made to produce a shoe or boot which will provide for a proper ventilation, or more particularly a circulation of air through the substantially dead air space surrounding the foot which will avoid the heat condition incident to the confinement of the foot within the leather covering.

It has been found by continued observation that the portion of the foot most subjected to perspiration is the underneath portion of the toes, for here the parts are more closely confined by reason of the usual heavy leather box toe employed in shoes and any air which may enter the shoe from the top while being worn does not find its way to the toe portion of the shoe.

The primary object of the present invention is the provision of a ventilating means for shoes in which the usual heavy leather box toe is eliminated and in which there is substituted for such box toe a light metallic structure made up of two independent parts, shaped to complete the shape of the shoe at this point, and constructed and arranged to provide for a more or less active circulation of air around and beneath the toes of the wearer.

The invention is illustrated in the accompanying drawing, in which:—

Fig. 1 is a perspective view, partly broken out, illustrating the application of the invention to a shoe.

Fig. 2 is a broken longitudinal section through the perforated box toe and the insole cooperating therewith.

Fig. 3 is a plan view of one section of the perforated box toe.

Fig. 4 is a plan view of the other section of the perforated box toe.

It is to be understood that the usual heavy leather box toe built into shoes is dispensed with for the purpose of the present invention, and that as a substitute there is provided a

metallic box toe made up of an outer section 1 and an inner section 2. The outer section, shown more particularly in Fig. 4 is made up of a plate 3 shaped to correspond with the shape and size of the toe of the shoe, and 55 formed at the forward end to provide a rounded upstanding wall 4, of outline shape corresponding to the toe of the shoe. The plate portion is secured in the shoe proper, so that the toe portion 4 serves to shape the 60 completed toe. This wall 4 is perforated throughout, and the upper surface of the plate 3 is provided with upstanding ribs 5, preferably of irregular outline and extending 65 from near the rear edge to the forward edge 70 of the plate.

The inner section is of similar shape to the outer section, including a bottom plate 6 and an upper wall 7, which latter is marginally connected to the side edges of the 70 plate 6, and is curved upwardly therefrom to form a section corresponding to the desired shape of the toe of the shoe. This inner section 2 is formed throughout its full 75 area with a series of perforations, as 8, the full area of the bottom plate 6 and upper wall 7 being perforated. The perforations extend throughout the full area of this section, the size and relative locations of the perforations being unimportant, as long as there is 80 no substantial area free of perforations.

The inner section 2 is fitted into the outer section 1, the forward portion of the wall 7 of the inner section fitting into the rounded wall 4 of the outer section, with the plate 85 6 of the inner section resting on the ribs 5 of the plate 3 of the outer section.

In connection with the toe box, there is provided an insole 9 having an outline shape to correspond with that of the foot of the wearer, which insole is formed with a series 90 of ventilating perforations 10 throughout its full area. This insole in its forward portion 11 is of less thickness than the remaining portion, being cut away on its under side to receive the bottom plate 6 of the inner section of the toe box, thus compensating for the thickness of the toe box in the fit of the insole.

The inner section 2 and also the insole is 100

preferably covered by a fabric covering, such as linen 12, which covering is of course perforated in accordance with the perforations in the metallic section and in the insole. The insole is preferably constructed of cork, and the upper surface is to present a smooth contact surface for the foot of the wearer, even within the toe box.

5 The interior of the shoe proper is to be lined with linen or the like, the primary idea of these coverings and linings being to provide against contact of the foot with the usual leather, with the resultant heating incident to such contact.

10 15 The outer portion of the shoe toe is to be covered with the usual tip 13, which is stitched to the vamp in the usual manner, and is formed with perforations 14, such as are usually employed as ornamental features of the tip. These perforations in the present use, however, are designed to serve as means for admitting air to the interior of the toe for ventilating purposes. If the usual tip edge perforations 15 are used, those nearest the vamp are to be sealed on the inner side of 20 25 the tip by a suitable strip, to prevent entrance of water.

15 20 The sections of the toe box are interconnected by fitting the rounded wall 7 of the inner section into the rounded wall 4 of the outer section. The inner section is provided with a projection 25 on the forward surface of the wall 7 which in contacting with the inner surface of the wall 4 of the outer section to maintain these walls 4 and 7 in spaced relation except the junction at the free edge of the wall 4, as clearly shown in Fig. 2. The wall 7 of the section 2 is formed with an elongated opening 16 serving to permit a 30 35 sewing connection as by stitches, with the edge of the upper to hold section 2 in place, the stitches passing readily through the opening 16.

40 45 The air admitted through the openings in the tip is caused to circulate through the channels provided by the ribs 5, between the plates 3 and 6 and up through the perforations of the walls 7, meanwhile passing between and around the toes of the wearer. 50 55 This circulation is a constant one and maintains the toes free of perspiration or undue heat and insures comfort and dry feet.

55 60 The metallic parts are constructed of aluminum to save weight without sacrificing strength, though the invention contemplates any appropriate material for these purposes.

60 65 By the use of the term shoe herein, it is obviously intended and should be understood as covering all types of footwear to which the invention is applicable, and that no restriction is contemplated by specific terms as to material or parts.

I claim:—

65 70 1. A ventilated shoe including a metallic box toe including a bottom perforated wall,

70 75 a rounded perforated upper wall, the outline shape of the box conforming to that of the toe of the shoe, and a perforated insole for use in the shoe and recessed to receive the bottom of the box toe, said box toe and insole being covered with fabric formed with continuations of the perforations in the box toe and insole, and a perforated metallic section conforming to the shape of the toe of the shoe and into which the metallic box toe and insole are fitted.

75 80 85 2. A shoe having a conforming metallic box toe having the bottom wall formed with perforations, the top wall formed with perforations, the shoe including a metallic tip overlying and receiving the box toe, said metallic tip being perforated to admit air to and through the perforations in the box toe, the tip including a bottom underlying and spaced from the bottom of the box toe.

85 90 95 3. A shoe including a metallic box toe receiving section having a shoe toe conforming perforated upper wall and an imperforate bottom formed with spacing ribs, and a perforated box toe seated within and spaced in part from said upper wall, the bottom of the box toe resting upon the ribs to define channels beneath said box toe.

95 100 105 4. A shoe including a metallic box toe receiving section having a shoe toe conforming perforated upper wall and an imperforate bottom formed with spacing ribs, and a perforated box toe seated within and spaced in part from said upper wall, the bottom of the box toe resting upon the ribs to define channels beneath said box toe, the box toe being perforated throughout its area to admit entry of air through the channels provided by the toe section to the interior of the box toe.

105 110 115 5. A shoe including a metallic box toe receiving section having a shoe toe conforming perforated upper wall and an imperforate bottom formed with spacing ribs, a perforated box toe seated within and spaced in part from said upper wall, the bottom of the box toe resting upon the ribs to define channels beneath said box toe, the box toe being perforated throughout its area to admit entry of air through the channels provided by the toe section of the interior of the box toe, and a perforated insole interfitting with the box toe and having a perforated portion to overlie the perforated bottom of the box toe.

115 120 125 6. A shoe including a metallic box toe comprising an outer section and an inner section, each section comprising bottom plates, and the sections interfitting in use, means for spacing the bottom plates when the sections are interfitted, and means for permitting free passage of air through the sections.

125 130 7. A shoe including a metallic box toe including an outer section having a bottom plate and an upstanding rounded wall, an inner section having a bottom plate to overlie the bottom plate of the outer section and

an upstanding wall to fit within the upstanding wall of the outer section, the upstanding walls of both sections being perforated and spaced apart throughout the greater portion of their areas, and means carried by the bottom plate of the outer section to space the bottom plates of the sections apart for air passage.

8. A shoe having a conforming metallic box toe having the bottom wall formed with perforations and a top wall formed with perforations, the shoe including a metallic tip overlying and receiving the box toe, said tip having an imperforate bottom wall underlying the bottom wall of the box toe and spaced therefrom, said tip having an upper wall overlying and spaced from the top wall of the box toe and of less length than said top wall of the box toe.

9. A shoe having a conforming metallic box toe with a perforated bottom wall and a perforated top wall, a metallic tip overlying and receiving the box toe, said tip having an imperforate bottom wall substantially of the length and width of the bottom wall of the box toe, the bottom wall of the tip being spaced from the bottom wall of the box toe, said tip having a perforated upper wall of less dimension lengthwise of the shoe than its bottom wall.

30 In testimony whereof I affix my signature.
